UNITED STATES PATENT OFFICE

GUSTAV E. JANSSON, OF ATLANTIC, MASSACHUSETTS, ASSIGNOR TO CONDIT ELECTRICAL MANUFACTURING CORPORATION, OF HYDE PARK, MASSACHUSETTS, A CORPORATION OF MASSACHUSETTS

SUSPENSION POTENTIAL TRANSFORMER

Application filed February 27, 1931. Serial No. 518,725.

This invention relates to improvements in 5 transformers and has for its object the provision of a voltage transformer which makes possible the connection of low tension instruments and other power consuming control apparatus to a high tension power system, and particularly to a high tension transmission line, without resorting to the costly constructions of the usual high tension electromagnetic potential transformer.

The primary winding of an electromagnetic transformer must be connected electrically to the high tension line and consequently must be insulated both from its core structure and the secondary winding by insulation capable of withstanding the full line voltage. With modern transmission voltages in the order of 110,000 to 220,000 volts, the insulation necessary adequately to insulate the line 10 voltages becomes very bulky and the transformer is accordingly expensive.

In accordance with this invention a potential transformer of the usual electromagnetic type is employed, the windings of which are 15 insulated only for a relatively moderate voltage which presents no difficult problems of insulation, and the primary winding of the transformer is connected electrically with the high tension line to be controlled through 20 a plurality of interposed serially electrically connected voltage impedance units which are mechanically connected in a string and are suspended, as from the high tension line, by means of suspension type insulators which 25 are interposed between and mechanically connect the adjacent units. As thus arranged the insulation between the units is in series and although the insulation between any two adjacent units is insufficient to withstand the 30 potential of the line, the combined insulation between all the units is sufficient to insulate the transformer unit, which is the most remote unit of the string, from the high tension line. The provision of a multi-unit suspension type voltage transformer as above 35 set forth constitutes one of the objects of this invention.

It is a further object of the invention to 40 provide a voltage transformer of this type 45 wherein the voltage drop between the high

tension line and the control circuit is obtained by means of a plurality of serially electrically connected reactance units the core structures of which are mechanically connected and are insulated from each other by 55 suspension type insulators.

A still further object of the invention is to provide a voltage transformer of the above type in which certain of the reactance units are wound of material having high electrical 60 resistance.

A yet further object is the provision of an impedance unit for a multi-unit suspension type voltage transformer having provision whereby a varying number of standard 65 units may be connected together in series to vary the insulation between the high tension line and the low tension control circuit.

A yet further object is the provision of an 70 improved construction for a secondary transformer which will be reliable in service and cheap to manufacture and install.

A further object is generally to improve the methods and apparatus for deriving relatively small amounts of power at low tension 75 from high tension systems.

Fig. 1 is a side elevation partly in section of a voltage transformer embodying the 80 invention.

Fig. 2 is a plan view of one of the reactance units of Fig. 1.

Fig. 3 is a section through the upper leg 85 of a magnetic core taken on line 3-3 of Fig. 2.

Fig. 4 is a sectional elevation of a modified construction for the reactance units.

Fig. 5 is a side elevation partly in section 90 of another form of the invention in which the units thereof are enclosed in compound filled housings.

Fig. 6 is a plan view of a unit of Fig. 5.

The voltage transforming device embodying the invention includes a plurality of serially electrically and mechanically connected electromagnetic units arranged as a suspension string, one end unit of which is adapted to be connected electrically with a high tension line to be controlled and the other and remote unit of which is adapted 95 to be connected to a low tension control circuit.

cuit. The several units of the device are mechanically connected by means of interposed insulating members which also constitute means for electrically insulating adjacent units from each other, a suitable number of units being employed so that the combined insulation between the several units will be sufficient to insulate the most remote unit from the high tension line.

10 The lowermost unit of the string comprises an electromagnetic transformer. As shown in Fig. 1, said transformer includes a laminated core member 10 which constitutes a closed magnetic circuit on one leg of which the primary and secondary windings 12 and 14 are supported in insulating relation with said core structure and with each other. Said windings 12 and 14 are insulated from said core 10 by means of spaced concentric inner 15 and outer insulating tubes 16 and 18 which surround the right hand core leg and which are supported at their lower ends by the bottom leg 20 of said core. Said bottom leg 20 is provided with plates 22 at its opposite 20 sides between which the laminations of the core 10 are clamped by bolts 23 which extend through said plates and laminations. Said plates 22 have outstanding flanges 24 and are provided with lateral projections 26 which 25 extend beyond said core structure beneath the bottom ends of said tubes 16 and 18 and constitute a support therefor. Said secondary winding 14 is located within the annular space between and intermediate the length 30 of said tubes and has its terminal leads 28 extended downwardly through said annular space and through a bushing 30 which is carried by and insulates said leads from the flange 24 of a side plate 22, whereby to carry 35 said leads below and insulate them from the core structure. Said inner tube has an integral outstanding cape 32 at its upper end which is formed with an annular recess 34 in its lower face into which the upper end of 40 the outer tube 18 extends, thus providing a weatherproof closure for the annular space between said tubes. Said outer tube 18 is provided with a similar cape 36 below the cape 32 which overhangs the primary winding 12 and also serves to greatly increase the 45 surface leakage path between the high tension primary winding and the core structure. Said primary winding is also enclosed in a weatherproof housing which includes the outer insulating cylinder 38 which surrounds 50 said winding and a frusto-conical cylinder 40 which overlies said winding and said cylinder 38. The outer insulating tube 18 is formed with a downwardly and outwardly 55 directed peripheral flange 42 located beneath the cape 36 which overlies the top edge of cylinder 40. The primary winding is thus 60 protected from the weather. A terminal lead 44 of said primary winding is extended downwardly within the housing cylinder 38 and

through an insulating bushing 46 which is carried by the flange 24 of a side plate 22 of the core structure and is carried to a ground connection, not shown. The other lead 48 of said winding is brought out through a downwardly inclined passage 50 in the cylinder 38 adjacent the upper end thereof and is extended upwardly and is connected electrically to the next upper unit which will be hereinafter described.

70 The primary and secondary windings of the transformer unit are additionally protected against ingress of moisture by means of a normally solid insulating compound which is introduced in a heated and fluid condition into the annular spaces 52 and 54 above and below said primary winding and also into the spaces 56 and 58 above and below said secondary winding. The upper leg of the core structure is also provided with side plates 60 similar to the plates 22 having outstanding flanges 61 and bolts 23 extend through said side plates 60 and the laminations therebetween and secure said plates securely to the core structure.

75 The primary winding 12 of the transformer unit above described is not intended to be insulated from the core structure and from the secondary winding 14 for the total voltage of the high tension line but is adapted to be insulated only for some small part of said high tension line voltage, which insulating can be accomplished without great difficulty. For example, the insulation of said primary winding 12 may be designed for 13,500 volts which can be readily insulated without resorting to expensive insulating constructions.

80 In accordance with the invention the transformer unit may be the same for a wide range of high tension line voltages since the voltage drop between the high tension line and the primary winding 12 of the transformer is adapted to be subdivided between a plurality of serially connected impedance units, the 85 number of which will be increased with increasing line voltage. Said units can be reactive units, where the impedance is mainly reactive, or they can be resistance units, where the impedance is caused by the resistivity of the windings. The impedance provided by the units also can be both resistive and reactive, as where the electromagnetic winding is composed of a conductor having substantial resistance. For average use, however, it is preferred to have mainly a reactive impedance.

90 100 105 110 115 120 125 130 Said impedance units, two of which are illustrated in Fig. 1, each include a laminated core structure 62 which is similar in construction to the core 10 of said transformer unit and which includes upper and lower side plates 64 and 66 having oppositely and outwardly extended flanges 68 and 70. The similar legs, as the right hand legs, of said

cores are each surrounded by an insulating tube 72 having an upper outstanding cape 74 which overhangs a multi-turn reactance winding 76 and provides an extensive surface creepage path between the upper high tension end of said winding and the core. An outer cylindrical housing 78 surrounds said reactance winding and extends upwardly from the lower leg of said core to a point beneath the cape 74. An insulating cylinder formed of bakelite or other fibrous insulating material has a downwardly and outwardly flared skirt 79 which overhangs the upper end of said cylindrical insulating tube 78 and has its inner end extended upwardly within a recess 80 beneath said cape 74, thus to provide a weatherproof closure for the annular space between the tube 72 and housing 78 which is occupied by said winding 76. A body of normally solid insulating compound 82 is introduced into the annular space below said winding 76 while in a heated and fluid state whereby to seal the space and prevent access of moisture to the winding. The upper terminal leads 86 of said reactor windings are brought out through downwardly inclined passages 88 in the insulating cylinder 78 and extend upwardly for connection with the next upper unit. The lower leads 90 of said windings are electrically connected with the core 62 and with the lead 86 of the next lower unit by means of a double lug connector 92 which is secured to the core 62 by means of the clamping bolt 94.

Each impedance unit is adapted to be thus connected in series with the adjacent units, a sufficient number of impedance units being employed to provide the required drop between the high tension line and the primary winding 14 of the lowermost electromagnetic transformer unit. The uppermost impedance unit has its upper terminal lead 86 electrically connected with the high tension line and the lowermost impedance unit has its lower terminal lead 90 electrically connected with the transformer primary winding 12.

Means are provided to insulate the core structures of the several units one from another which means also constitutes the mechanical support for the units. To this end a suspension type insulator 96 is provided between and spaces apart the adjacent units. Said insulators may be of the usual suspension cape type known as strain insulators which are provided with a central outstanding cape 98. Each of said insulators also has a metal attaching cap 100 above the cape thereof which is provided with upstanding attaching ears 102 and with a lower depending metal tongue 104 below the cape which is arranged in a vertical plane at right angles to the ears 102. Said tongue 104 is pivotally connected to the core structure of the adjacent lower unit by means of an attaching clamp having complementary clamping

members 106. As best shown in Fig. 3 said clamping members 106 have upstanding spaced and parallel lugs 108 between which the depending tongue 104 of the insulator is loosely received and is pivoted on a pin 110 which extends through said lugs and the tongue. Said clamping portions are further provided at their lower end with integral depending flanges comprising the vertical portions 112 which overlie the extended ends of the flanges 68 of the core structure and inwardly reflexed horizontal portions 114 which extend beneath said flanges 68, thus to provide opposed horizontal recesses 116 in which the flanges of the opposite side plates 64 are closely received. A clamping bolt 118 extends through the body portions of said attaching members 106 and clamps said members fixedly in position on the core structure while permitting free pivotal movement of the tongue 104 relative to the lugs 108. The insulator 96 is secured to the unit above it by means of a T-shaped attaching member 120 which comprises a plate 122 that is secured to the lower outstanding flanges 70 of the core structure by means of bolts 124 and an integral depending flat tongue 126 which lies in a plane normal to the vertical plane of the core structure and is received between and is pivotally connected with the upstanding ears 102 of said insulator cap by means of a pivot pin 127. As thus arranged the connection between two adjacent impedance units permits pivotal movement of the connected units in two vertical planes which are normal to each other and which prevents unnecessary strain on the attaching members due to laterally applied wind forces. The attaching members 120 and the clamping members 106 are secured to the flanges 68 and 70 of the lower and upper core structures at a point which is in a vertical plane including the center of mass of the units, so that the connected units hang in vertical alignment.

Figs. 5 and 6 illustrate another embodiment of the invention in which the impedance units and the lower transformer unit are enclosed within compound filled metallic housings. As here shown, the core structures 10a and 62a of the transformer and impedance units are each enclosed within a housing comprising a generally cylindrical side wall 128, open at the top and bottom, having a cover 130 which provides a weatherproof closure for the open top thereof. Said cover accordingly has a depending peripheral flange 132 which overlies the outer surface of said casing wall 128 and which is permanently secured thereto as by soldering or welding. The magnetic core structure 10a and 62a of said transformer and impedance units are located eccentrically within the housing and the housings are provided with outstanding vertical extensions, or channels, 133 into

which the core projects, thus to reduce the volume of the housing. Said core structures, which may be identical in construction, include a plurality of thin laminations which are firmly gripped between pairs of side plates 60a and 22a, which are disposed on opposite sides of the upper and lower legs respectively of said core laminations, by bolts 23a located at the corners of said cores. Said 10 plates also have oppositely and outwardly extended flanges 61a and 24a at their top and bottom edges respectively. The cover 130 is adapted to be fixed to the flanges 61a and the securing means therefor constitutes the lower 15 of a pair of pivotally connected attaching members 134 and 135 for interconnecting the core structures of adjacent units.

Said lower attaching member 134 comprises a generally elongated block which rests 20 upon the top of cover 130 transversely of the core and overlying the flanges 61a thereof. Said block is provided with an elongated recess 136 in its lower face adjacent the cover into which project integral upstanding necks 25 138 of said cover 130. Said necks, which are preferably formed by expressing the material of said cover, are provided with vertical passages 139 to receive bolts 140 which pass through said block and the flanges 61a and 30 are screw-threaded into rectangular bars 142 beneath said flanges. The attaching members 134 are provided with central and spaced upstanding lugs 144 which are pivotally connected by a pin 146 to a depending tongue 35 148 of said upper attaching member 135 which is received between said lugs 144. One of the clamping bolts 23a, as the lower left-hand corner bolt is extended outwardly 40 through the housing, whereby to connect the housing and core at this point and relieve the attaching member 134 of strain due to the eccentric attachment of the core thereto. The upper attaching member 135 constitutes the lower attaching pin of a cape insulator 96a, 45 one of which is interposed between adjacent units. Said cape insulators also have an upper metal attaching cap 100a provided with spaced lugs 102a which are normal to the lower tongue 148. A plate 122a is secured to 50 the lower flanges 24a by means of bolts 124a and has a central depending tongue 126a which lies between the lugs 102a and is pivotally connected therewith by a pin 127a.

The right-hand leg of the core 10a which 55 carries the primary and secondary transformer windings 12a and 14a is surrounded by an insulating tube 149 preferably composed of bakelite by which the secondary winding 14a of the transformer is insulated 60 from the core. The primary winding 12a is insulated from said core structure and also from the secondary winding 14a by means of inner and outer telescoping insulating tubes 150 and 151 which are provided with corrugations 152 at their upper and lower ends re-

spectively, thus to provide increased surface leakage paths between the primary winding and the core. Said telescoping tubes are supported by and above the lower leg of the core structure 10a. To this end spaced side plates 22a carried thereby are extended at 154 beyond the core structure. An insulating plate 156 on which the lower end of the outer tube 151 rests is supported above the lower leg of the core 10a by means of a washer 158 which rests upon said lower leg and surrounds the right-hand leg of the core beneath said plate. The plates 22a are provided with outstanding flanges 24a one of which supports a pair of insulating bushings 160 and 162. The terminal leads of said transformer secondary are brought out through one of said bushings as the bushing 162 and are adapted to be connected with the low tension control circuit. A terminal lead 166 of said transformer primary is extended through said other bushing 160 and is adapted to be connected to ground. The other terminal lead 168 of said transformer primary is brought out through the casing wall 128 90 through an outwardly and downwardly inclined insulating bushing 170. Said bushing is secured detachably in a weather tight manner to the outside of the casing wall 128 by means of a bolted sleeve 172 and is provided at its outermost end with a metal cap 174 having an externally screw-threaded neck 176. The lead 168 passes through several layers of packing material 178 disposed within an internally screw-threaded cap 180 100 through which said lead extends and which is screw-threaded onto said neck 176 and compresses said packing about the lead 168.

The core structures of the several impedance units each carry a multi-turn reactance winding 76a which is insulated from the core by means of telescoping inner and outer porcelain tubes 182 and 184, the latter of which carries the winding 76a externally thereof. The outermost tube 184 is supported above the core structure by means of an insulating disc 186 and a lower insulating washer 188 both of which are loosely threaded over the right-hand leg of the core. The innermost tube 182 is formed with an enlarged corrugated upper end portion 190 which overlies and rests upon the upper end of the outer tube 184 and supports said inner tube; and said outermost tube has a similar corrugated lower end portion 191 which constitutes a support for the reactance winding 76a. 110

The upper terminal lead 192 of said reactance winding is brought out through the casing wall 128 through a downwardly and outwardly extended bushing 194 which is similar in construction to the bushing 170 of the transformer unit above described. The lower terminal of said winding is connected with the lead 192 of the next lower 120 130

impedance unit, or in the case of the lowermost impedance unit with the lead 168 of the transformer primary winding. The lead 192 or 168, as the case may be, extends 5 through an insulating bushing which passes through one of the outstanding flanges 24a of the lower leg of the core structure.

The space within the housing is adapted 10 to be filled with a normally solid insulating compound 196 which is introduced into the housing in a heated and liquid state and which occupies the housing to a point below the core structure therein. For the purpose of filling the units they are inverted during 15 the process of pouring in the compound and until the compound has set.

In Fig. 4 a modified construction for an impedance unit is shown in which the multi-turn winding 76b is wound in two parts 198 and 200 which are insulated from the vertical leg of core 10b by a pair of upper and lower axially aligned and vertically spaced porcelain tubes 202 and 204, each porcelain tube having a winding carried externally thereof. 25 Said lower tube which rests on the core structure at its bottom end is provided with an enlarged and externally corrugated portion 206 at its lower end adjacent the core structure on which the reactance winding 200 is supported in spaced relation with the core. The upper tube 202 has a similar enlarged portion 208 at its upper end which determines the upper position which the winding 198 can occupy. The space between the confronting end faces of said tubes 202 and 204 is occupied by an insulating washer 210 which is carried by the vertical core leg and which centers an annular insulating cylinder 212 which rests upon the upper end of the winding 200 and constitutes a support for the upper winding 198. The transformer can also be constructed in this manner, if desired.

Said reactance windings 198 and 200 have 45 their common intermediate terminal leads 214 electrically connected together and to said core structure 10b by means of a lug 216 which is secured to the core by a bolt 218, thus giving the core a potential which is intermediate that of the end terminals 220 and 222 of said upper and lower coils respectively. Consequently the core need be insulated 50 for a voltage representing one-half the combined voltage drop across the reactance coils.

As in the modification shown in Figs. 1 and 5, the portion of the winding which is at the highest potential is adapted to be located adjacent the enlarged corrugated end of the insulating bushing. To this end the coils are bank wound, that is, the turns which occupy the same radial plane of the coils are wound progressively beginning adjacent the enlarged portions of the tubes and continuing 65 axially along the tubes to the confronting ends thereof at which the intermediate termi-

nals of the coils are located. In this manner those portions of the winding which differ greatest from the potential of the core are located adjacent the enlarged ends of the tubes where they are most effectively insulated from the core. This construction of insulating shells permits the coils to be form-wound and thereafter slipped upon the shells and thus provides an arrangement that can be economically manufactured. 70 75

Where it is important to have the secondary voltage of the control circuit as nearly as possible in phase with the line voltage, the reactance windings may be composed of a high resistance wire which has the effect of correcting to a large degree the variation in the phase angle of the low tension secondary and high tension voltages. 80

Various modifications may be made in the construction without departing from the 85 scope of the invention.

I claim:

1. A high tension suspension type transformer comprising a string of superposed units each including a core structure comprising a magnetic circuit having vertical and upper and lower horizontal legs, a winding surrounding a vertical leg of said core structure and insulated therefrom, and a weatherproof housing enclosing said winding, and means for suspending the units one from another comprising an insulating suspending member which is connected with the lower horizontal leg of the upper core and the upper horizontal leg of the next lower core and electrically insulates said cores from each other. 90 95

2. An electromagnetic unit for a high tension suspension type transformer including a core structure comprising a closed magnetic circuit, an insulating tube surrounding a leg of said core having an outstanding peripheral flange at one end thereof, a winding carried by said tube and insulated from said core thereby having high and low tension terminal leads and having the high tension lead thereof located adjacent the flange and the low tension lead located adjacent the unflanged end of said tube, a weatherproof housing enclosing said winding, and means for pendentially supporting said unit by said core. 100 105 110 115

3. An electromagnetic unit for a high tension suspension type transformer including a core structure comprising a closed magnetic circuit, an insulating tube surrounding a vertical leg of said core having an outstanding cape, an insulating shell concentric with and spaced from said tube having its upper end terminated beneath the cape thereof, a winding located in the annular space between said tube and shell, and suspending means for said unit attached to said core structure. 120 125

4. An electromagnetic unit for a high tension suspension type transformer including a 130

- vertical leg of said core structure having an annular outstanding flange at its upper end formed with an annular groove in its lower face, an outer insulating tube concentric with said inner tube having its upper end located within said annular groove and having an annular outstanding flange adjacent the upper end thereof, an insulating shell surrounding and concentric with said tubes having its upper end terminated beneath the flange of said outer tube, a secondary winding located in the space between said inner and outer tubes having a terminal extended downwardly in the space between said tubes, a primary winding disposed in the space between said outer tube and shell and having a terminal lead extended downwardly in the space therebetween, said primary winding also having a second terminal lead which extends through said shell beneath the flange of said outer tube, and an insulating compound disposed within the spaces between said inner and outer tubes and between said outer tube and shell.
12. In a high tension suspension type transformer including a plurality of interconnected electromagnetic units, a transformer unit including a continuous core structure comprising a closed magnetic circuit, an inner insulating tube extended on a vertical leg of said core having an outstanding flange at its upper end, a secondary winding surrounding said inner tube and located beneath said flange, an outer insulating tube concentric with said inner tube having its upper end terminated beneath the flange of said inner tube and having an outstanding flange adjacent its upper end, a primary winding surrounding said outer tube beneath the flange thereof, a cylindrical shell surrounding said primary winding having its upper end terminated beneath the flange of said outer tube, said core having a laterally extended lower leg which constitutes the support for said tubes and said shell, said lower leg including an outstanding flange having insulating bushings extended therethrough one of which projects upwardly into the space between said tubes and the other of which projects upwardly into the space between said outer tube and shell, terminal leads for said primary and secondary windings extended downwardly through said bushings, and means having a connection with the upper leg of said core for suspending said unit.
13. In a high tension suspension type transformer including a plurality of interconnected electromagnetic units, a transformer unit including a continuous core structure comprising a closed magnetic circuit, an inner insulating tube extended on a leg of said core having an outwardly extended annular flange at its upper end which is formed with an annular recess in its lower face, an outer insulating tube surrounding and spaced from said inner tube having its upper end terminated within said recess, said outer tube having an outwardly extended flange adjacent its upper end, an external insulating shell surrounding and spaced from said outer tube and having its upper end terminated within the confines of the flange of said outer tube, secondary and primary windings located in the spaces between said inner and outer tubes and said outer tube and shell respectively, a pair of side plates secured to the lower leg of said core and extended laterally beneath said tubes and shell and constituting a support for the lower ends thereof, one of said side plates having an outstanding flange, said secondary winding having a terminal lead which is extended downwardly below said core structure, and an insulating bushing carried by said flange through which said lead is extended.
14. In a high tension suspension type transformer including a plurality of interconnected electromagnetic units, a transformer unit including a continuous core structure comprising a closed magnetic circuit, an insulating tube surrounding a vertical leg of said core, a secondary winding surrounding said tube, an outer and concentric tube surrounding said secondary winding, a primary winding surrounding said outer tube, an insulating cape carried by said inner tube forming a closure for the space between said tubes, said outer tube having a downwardly and outwardly directed flange adjacent its upper end, an insulating shell surrounding said primary winding having its upper edge terminated beneath said flange, a pair of side plates carried by the upper leg of said core having oppositely and outwardly directed flanges, means to suspend said unit including attaching means having a detachable connection with the flanges of said side plates, a pair of side plates carried by the lower leg of said core having integral projections which extend beneath and constitute the support for said tubes and shell, at least one of said lower side plates having an outstanding flange, terminal leads of said windings extended downwardly below said core structure, and insulating bushings carried by said flange through which said leads are extended.
15. In an electromagnetic unit for a high tension suspension type transformer including a plurality of interconnected suspension units, the combination of a continuous core structure which constitutes a closed magnetic circuit, an insulating tube surrounding a vertical leg of said core having an annular outstanding cape at its upper end, a winding surrounding said tube beneath said cape, an insulating shell surrounding said winding having its upper end terminated beneath said cape and its lower end terminated below said winding, pairs of opposed side plates carried

by the upper and lower legs of said core having oppositely directed outstanding flanges, and means having a detachable connection with the flanges of said upper and lower legs for connecting said unit with adjacent upper and lower units.

16. In a high tension suspension type transformer including a plurality of interconnected electromagnetic units, a transformer unit comprising a continuous core structure, a secondary winding surrounding and insulated from a vertical leg of said core and spaced apart from the upper and lower legs thereof, a pair of telescoping inner and outer concentric tubes surrounding said secondary winding, said inner tube having an enlarged upper end portion which overlies the upper end of said outer tube and said outer tube having an enlarged lower end portion, and a primary winding surrounding said outer tube between the enlarged end portions of said tubes.

17. In a high tension suspension type transformer including a plurality of interconnected electromagnetic units, a transformer unit comprising a continuous core structure, a secondary winding located on a vertical leg of said core and insulated from said core, inner and outer telescoping insulating tubes surrounding said secondary winding, said outer tube having an enlarged corrugated lower end portion which is supported by the lower leg of said core and said inner tube having an enlarged corrugated upper end portion which rests upon the upper end of said outer tube, a primary winding surrounding said tubes between the enlarged end portions thereof, and a weatherproof housing enclosing and carried by the upper leg of said core and enclosing said transformer windings.

18. In a high tension suspension type transformer including a plurality of interconnected electromagnetic units, a transformer unit comprising a continuous core structure, a secondary winding located on a vertical leg of said core and insulated from said core, inner and outer telescoping insulating tubes surrounding said secondary winding, said outer tube having an enlarged corrugated lower end portion which is supported by the lower leg of said core and said inner tube having an enlarged corrugated upper end portion which rests upon the upper end of said outer tube, a primary winding surrounding said tubes between the enlarged end portions thereof, a housing enclosing and spaced apart from said telescoping tubes, and an insulating compound occupying the space within said housing.

19. In a high tension suspension type transformer including a plurality of interconnected electromagnetic units, a transformer unit comprising a continuous core structure, a secondary winding located on a vertical leg of

said core and insulated from said core, inner and outer telescoping insulating tubes surrounding said secondary winding, said outer tube having an enlarged corrugated lower end portion which is supported by the lower leg of said core and said inner tube having an enlarged corrugated upper end portion which rests upon the upper end of said outer tube, a primary winding surrounding said tubes between the enlarged end portions thereof, a metallic housing enclosing said core structure and transformer windings, said housing being open at the bottom, terminal leads for said windings extended downwardly through the open bottom of said housing, a downwardly and outwardly directed insulating bushing extended through the side wall of said housing, and a terminal lead for said primary winding extended through said bushing.

20. In a high tension suspension type transformer including a plurality of interconnected electromagnetic units, a transformer unit comprising a continuous core structure, a secondary winding surrounding and insulated from a vertical leg of said core, inner and outer telescoping insulating tubes surrounding said secondary winding, said outer tube having an enlarged and corrugated lower end portion located adjacent the lower leg of said core and said inner tube having an enlarged and corrugated upper portion which is located above and rests upon the upper end of said outer tube, a primary winding surrounding said outer tube above the lower enlarged portion thereof, a pair of side plates carried by the upper leg of said core having oppositely and outwardly extended flanges, an open bottom housing enclosing said core structure including a cover wall which rests upon said flanges, said cover and flanges having aligned passages therethrough and said cover having integral upstanding necks surrounding the passages therein, an attaching member for supporting said unit comprising an attaching block having a recess in the lower face thereof within which said necks project, and clamping bolts extended through said attaching block and the aligned passages in said cover and the flanges of said core.

21. An electromagnetic unit for a high tension suspension type transformer including a continuous core structure, inner and outer telescoping insulating tubes surrounding a leg of said core, said outer tube having an enlarged lower end portion adjacent the lower leg of the core and said inner tube having an enlarged upper end portion adjacent the upper leg of said core, a winding surrounding said telescoping tubes between the enlarged end portions thereof, a housing enclosing said core and winding, and attaching means having connections with said core structure at the upper and lower legs thereof for connect-

ing said unit with adjacent upper and lower units.

22. An electromagnetic unit for a high tension suspension type transformer including a continuous core structure, inner and outer telescoping insulating tubes surrounding a leg of said core, said outer tube having an enlarged lower end portion adjacent the lower leg of the core and said inner tube 10 having an enlarged upper end portion adjacent the upper leg of said core, a winding surrounding said telescoping tubes between the enlarged end portions thereof, attaching members having a connection with said core 15 at the top and bottom thereof arranged to connect said unit with adjacent upper and lower units, and a housing enclosing said core structure and winding which is open at the bottom having a top closure therefor 20 25 which is disposed between said core structure and the upper clamping member thereof.

23. An electromagnetic unit for a high tension suspension type transformer including a continuous core structure, inner and outer telescoping insulating tubes surrounding a leg of said core, said outer tube having an enlarged lower end portion adjacent the lower leg of the core and said inner tube having an enlarged upper end portion adjacent the upper leg of said core, a winding surrounding said telescoping tubes between the enlarged end portions thereof, pairs of opposed side plates carried by the upper and lower legs of said core structure having 30 35 oppositely and outwardly directed flanges, upper and lower attaching members connected with the flanges of said upper and lower plates having provision for connecting said unit pivotally with the adjacent upper and lower units, a housing enclosing said core structure and winding which is supported by the flanges of said upper leg, an insulating bushing extended through a flange of said lower leg, a second insulating bushing 40 45 extended downwardly and outwardly through a side wall of said housing, and terminal leads for said winding extended separately through said bushings.

24. In a suspension transformer, the combination of a string of electromagnetic units each comprising a magnetic core having top, bottom and side legs and a winding surrounding a leg of said core, the windings of the several units being connected electrical- 50 55 ly in series, and suspension insulators interposed between and mechanically flexibly connecting the cores of adjacent units of the string, said insulators comprising insulating bodies having upper and lower metal attach- 60 65 ing members carried by remote portions thereof, and means connecting said upper and lower attaching members pivotally with the bottom and top leg respectively of adjacent core structures.

25. Electrical apparatus comprising a

magnetic core, a pair of insulating tubes arranged in co-axial relation on the same leg of said core, each tube having an outstanding insulating flange at one end only thereof and said tubes being disposed with their tubular 70 bodies thereof adjacent each other and said flanges remote from each other, and a winding surrounding said tubes between said flanges.

In testimony whereof, I have signed my 75 name to this specification.

GUSTAV E. JANSSON.
